UNITED STATES PATENT OFFICE.

EDWARD L. BRADT, OF SHREVEPORT, LOUISIANA, ASSIGNEE TO FRED C. ARMBRUSTER,
OF SHREVEPORT, LOUISIANA.

MATERIAL-HANDLING APPARATUS.

Application filed March 10, 1926. Serial No. 93,669.

This invention relates in general to a material-handling apparatus especially adapted for loading or unloading material such as crushed stone, gravel, sand, clay, chert, coal, 5 or the like into or from open top railroad cars, wagons, trucks, or the like, as well as onto or from storage piles or the like.

The object of the invention is to provide a labor saving mechanical device by which 10 materials of the character mentioned may be quickly and easily loaded and unloaded into cars or other vehicles or onto storage piles and one of the important features of the invention resides in the fact that the material 15 handling apparatus embodying the present invention is adapted to be adjusted to carry out the loading throughout the entire extent of the car or vehicle in which the material is to be placed or from which the material is 20 to be taken.

Other objects and advantages reside in certain novel features of the construction, arrangement and combination of parts which will be hereinafter more fully described and 25 particularly pointed out in the appended claims, reference being had to the accompanying drawings forming a part of this specification, and in which:

Figure 1 is a fragmentary plan view showing 30 a loading device constructed in accordance with the present invention,

Figure 2 is a view thereof in side elevation,

Figure 3 is a fragmentary view showing 35 the extensible mast and associated parts in transverse vertical section.

Figure 4 is a sectional view taken on the line 4-4 of Figure 3, and

Figures 5, 6 and 7 are diagrammatic views 40 in elevation illustrating different positions of the parts of the apparatus embodying the present invention.

Referring to the drawings it will be seen 45 that the apparatus embodying the present invention includes a support which in the present instance is constituted by a wheeled platform which may be propelled or pulled in any suitable manner. A main shaft 2 is rotatably mounted in bearings 3 provided 50 therefor on the support 1 and this shaft 3 is driven by any suitable gearing illustrated for the sake of illustration as chain and sprocket gearing 4 from a power plant 5 which may be an internal combustion en-

gine, an electric motor, a steam engine or 55 any other type of prime mover.

An extensible mast, designated generally at 6, is provided and consists of telescoping sections 7 and 8, the section 7 being the inner section which is fixed in respect of axial 60 movement and the section 8 being the outer section which is movable axially with and longitudinally on the inner section 7. The inner section 7 is provided with trunnions 9 through which the main shaft 2 loosely extends. By virtue of this mounting on the main shaft the extensible mast is tiltable or adjustable angularly about the main shaft. Means is provided for controlling the tilting movement of the extensible mast 6 and 70 consists of a pair of segmental gears 10 formed on the lower ends of opposite sides of the inner sections 7 of the mast and meshing with pinions 11 fixed on an operating shaft 12 driven by chain and sprocket 75 gearing 13 from the main shaft 2, the drive being controllable at will by means of a clutch 14 which may be of any suitable type. The shaft 12 is held in any adjustment by 80 any suitable holding means which may consist of a brake 15 as illustrated in Figure 4.

The mast 6 consists, as indicated, of interfitting or telescoping tubular sections which are preferably of rectangular form in cross section and when the mast is extended the 85 section 8 slides upwardly on the section 7. Means is provided for controlling the sliding movement of the sections 8 and preferably consists of a winch 16 driven from the main shaft 3 by means of a gearing 17, the action 90 of the gearing being controlled by means of a suitable clutch 18. The winch 16 has cables 21 wound thereon and extended around guide pulleys 22 at the lower end of the section 7 and guide pulleys 23 at the 95 upper end of the section 7, the cables being attached at their lower ends to the sliding section 8, as indicated at 23a. Thus when the cables are wound on the winch 16 then the section 8 is elevated. The drum of the 100 winch 16 has a suitable brake attached thereto and holding the section 8 elevated. The gearing 17 may embody a suitable reversing means for driving the drum of the winch 16 in either direction.

A boom, designated at 25, is provided and 105 consists of two laterally extending arms 26 fastened to the opposite sides of the upper

end of the sliding section 8 of the mast. To the outer ends of the arms 26 which constitute the boom the upper end of the frame 27 of a bucket elevator, designated generally at 28, is pivotally connected. The bucket elevator 28 includes not only the frame 27 but an endless element 29 trained around sprocket wheels 30 pivoted on the frame 27, the endless element 29 carrying the buckets 31. To 10 the opposite sides of the lower end of the frame 27 combined guard and rest plates 32 are fixed and serve to provide a base or support for the lower end of the bucket elevator 28 in certain phases of the operation.

15 Means is provided for swinging the bucket elevator about its pivotal mounting and for holding it in any desired adjustment and this means consists of a pair of push bars 32 pivotally connected, as at 33, to the frame 27 of the bucket elevator and having racks 34 meshing with pinions 35 fixed on a pinion shaft 36 rotatably mounted in suitable bearings provided therefor on the section 8 of the mast. Rollers 37 are rotatably mounted on the section 8 of the mast and engage the smooth backs of the push bars to maintain the racks 34 engaged with the pinions 35.

20 The shaft 36 is held in any adjustment 30 by means of suitable braking mechanism 38 (see Fig. 1) and this shaft is driven from the main shaft 3 at the will of the operator. For the purpose of driving the shaft 36 and also for driving the bucket elevator, in all 25 adjustments of the extensible mast and in all adjustments of the elevator, the shaft 3 has fixed thereto oppositely disposed beveled gears 39 which mesh with a driven beveled gear 40 fixed to the lower end of a 30 vertical shaft 41 rotatably mounted in bearings provided therefor on the fixed section 7 of the mast. The shaft 41 is provided with a longitudinal key-way 42 with which the key of a sliding gear 43 co-acts whereby 45 to constrain the gear 43 to rotate with the shaft 41 while permitting the gear 43 to freely slide along this shaft. In order to cause the gear 43 to slide along the shaft 41 in accordance with the movement of the 50 outer movable section 8 of the mast, the section 8 has a transversely extending cross bar 44, the central portion of which is apertured to receive the shaft 41 and is suitably engaged with the hub of the gear 43. 55 This cross bar 44 operates in lengthwise slots 45 provided in the inner section 7 of the mast. The gear 43 meshes with oppositely disposed beveled gears 46 fixed to the inner ends of stub shafts 47 rotatably mounted 60 in bearings provided therefor in the movable section 8 and accommodated in slots 45 in section 7. The portions of the stub shaft 47 which project beyond the mast have sprocket wheels 48 and 49 fixed thereto, a sprocket chain 50 being trained over

the sprocket wheel 48 and over a sprocket wheel 51 fixed on the shaft 36. A clutch 52 is provided between the sprocket wheel 48 and the shaft 47 on which it is mounted so that the rotation of the shaft 36 may be 70 controlled at will. A sprocket chain 53 is trained over the sprocket wheel 49 and over a sprocket wheel 54 fixed to the shaft on which the bucket elevator 28 is pivoted and on which the upper sprockets 54 are secured. A clutch 55 is provided between the sprocket wheel 49 and the shaft 47 so that the actuation of the bucket elevator may be 75 controlled at will.

80 A chute, designated generally at 60, is provided and includes an upper section 61 fixed to the movable section 8 of the mast and movable therewith and a lower section 62 fixed to the stationary section 7 of the mast, the upper section 61 telescoping into 85 the lower section 62. The upper section 61 is provided with a flaring inlet or receiving mouth 63 positioned to receive the material from the buckets of the elevator 28. The lower end of the section 62 drops the material from the chute into a hopper 64 which drops the material onto a laterally extending conveyor 65 which carries the material to the point of discharge. The conveyor 65 includes an endless conveyor element 67 actuated by sprocket wheels 68 mounted on shafts 69, one of the shafts 69 being driven from the main shaft 3 by means of gearing 70 controlled by a clutch 75.

90 Figure 5 illustrates how the mast 6 may be tilted and the bucket elevator 28 swung inward to lift the bucket elevator up over the sides of cars where the sides are relatively high. Figure 6 illustrates how the bucket elevator may be swung inwardly to 105 make the mast more compact for transportation and Figure 7 illustrates how the bucket elevator 28 and the mast 6 may be swung and tilted respectively in order to move the material from the car for its entire 110 transverse extent. The machine may be moved along the car to remove the material from the car for its entire longitudinal extent.

115 I claim:

1. A material handling apparatus of the character described comprising a support, a vertically extensible mast, means for controlling the extension of the mast, means for mounting the mast for tilting movement on the support, means for controlling the tilting of the mast, a boom fixed to the mast and extending laterally therefrom, an elevator pivotally mounted on the boom, means for controlling the position of the elevator, an extensible chute mounted on the mast and extensible therewith, said chute having its upper portion disposed to receive the material from the elevator, and a laterally extending conveyor receiving the material 13

from the chute and conducting it to the point of discharge.

2. A material handling apparatus of the character described comprising a support, a vertically extensible mast, means for controlling the extension of the mast, means for mounting the mast for tilting movement on the support, means for controlling the tilting of the mast, a boom fixed to the mast and extending laterally therefrom, an elevator pivotally mounted on the boom, means for controlling the position of the elevator, and an extensible chute mounted on the mast and extensible therewith, said chute having its upper portion disposed to receive the material from the elevator.

3. A material handling apparatus of the character described comprising a support, a vertically extensible mast mounted on the support, means for controlling the extension of the mast, a boom carried by the mast, an elevator pivoted to the boom, means for controlling the position of the elevator, and an extensible chute mounted on the mast extensible therewith and receiving the material from the elevator.

4. A material handling apparatus of the character described comprising a support, a vertically extensible mast, means for controlling the extension of the mast, means for mounting the mast for tilting movement on the support, means for controlling the tilting of the mast, a boom fixed to the mast and extending laterally therefrom, an elevator pivotally mounted on the boom, means for controlling the position of the elevator including push bars pivotally connected to the elevator and having racks, pinions meshed with the racks, a pinion shaft on which the pinions are fixed, controllable means for driving said shaft, an extensible chute mounted on the mast and extensible therewith, said chute having its upper portion disposed to receive the material from the elevator, and a laterally extending conveyor receiving the material from the chute and conducting it to the point of discharge.

5. A material handling apparatus of the character described comprising a support, a vertically extensible mast, means for controlling the extension of the mast, means for mounting the mast for tilting movement on the support, means for controlling the tilting of the mast, a boom fixed to the mast and extending laterally therefrom, an elevator pivotally mounted on the boom, means for controlling the position of the elevator including push bars pivotally connected to the elevator and having racks, pinions meshed with the racks, a pinion shaft on which the pinions are fixed, controllable means for driving said shaft, an extensible chute mounted on the mast and extensible therewith, said chute having its upper portion disposed to receive the material from the elevator, and a laterally extending conveyor receiving the material from the chute and conducting it to the point of discharge.

ling the extension of the mast, means for mounting the mast for tilting movement on the support, means for controlling the tilting of the mast, including segmental gears carried on the lower end of the mast, pinions 55 meshed with the segmental gears, a shaft on which the pinions are fixed, controllable means for rotating the shaft, a boom fixed to the mast and extending laterally therefrom, an elevator pivotally mounted on the boom, means for controlling the position of the elevator, an extensible chute mounted on the mast and extensible therewith, said chute having its upper portion disposed to receive the material from the elevator, and a later- 60 65 ally extending conveyor receiving the material from the chute and conducting it to the point of discharge.

6. A material handling apparatus of the character described comprising a support, a vertically extensible mast including a relatively fixed section mounted on the support and a relatively movable section slidable on the fixed section, means for controlling the sliding movement of the movable section, a 70 boom fixed to the mast and extending laterally therefrom, an elevator pivotally mounted on the boom, means for controlling the pivotal movement of the elevator on the boom including push bars pivotally connected to the boom and having racks, pinions meshed with the racks and mounted on the movable section of the mast, means for driving the bucket elevator including a gear, a gear shaft mounted on the movable section 75 of the mast, a second gear shaft also mounted on the movable section of the mast and connected with the pinion shaft, means for driving said gear shaft in all adjustments of the movable section and including a vertical 80 shaft extending up through the mast, a gear splined on said vertical shaft, means for moving the gear splined on the vertical shaft in accordance with the movements of the vertical section, means for transmitting the 85 motion of said splined gear to the gear shafts, and means for driving the vertical shaft.

EDWARD L. BRADT.
